12 Claims. (Cl. 313—15)

1

My invention relates to gaseous electric discharge devices with an incandescent cathode in an atmosphere of inert gas or metal vapor, and particularly to discharge devices whose cathode has a thermo-ionically highly active surface and whose atmosphere contains vapor of alkali metal preferably of potassium, rubidium or cesium.

Such alkali metal vapors facilitate obtaining a high specific electron emissivity of the cathode surface and reduce the voltage drop of the discharge between cathode and anode.

The emission of electrons from the cathode has a cooling effect on the cathode. The ingress of electrons into the anode causes heating of the anode. That is, due to the emission of electrons, heat of evaporation is drawn from the cathode, while heat of condensation is given off to the anode. In gas discharge devices operating with a high specific electron emission at the cathode surface and a low voltage drop of the discharge between cathode and anode, this transfer of heat from cathode to anode plays a considerable role compared with the heat losses within the gas discharge proper. The vaporization heat of the electrons must be constantly refurbished to the cathode, and the heat of condensation must be constantly carried off from the anode. This heat transfer therefore increases the losses in the gas discharge device and aggravates the cooling requirements.

It is an object of my invention to minimize or virtually eliminate these disadvantages. In other words, my invention aims at improving the heat economy of gaseous discharge devices, especially those containing an alkali vaporous atmosphere, and thus to improve the stability of operation.

Another, ancillary object is to simplify the cooling requirements of such tubes or to do away with the necessity of providing special cooling means.

In order to achieve these objects, and in accordance with one of the features of my invention, I couple the anode in thermally radiative respects closely with the cathode and give the anode such a normal operating temperature that a considerable portion of the condensation heat caused by the flow of electrons into the anode is returned to the cathode by heat radiation and contributes essentially to maintaining the cathode at its normal temperature, thus providing a considerable portion of the vaporization heat required at the cathode.

Of course, this is possible only if the anode has a higher operating temperature than the cathode and if there is a close thermal radiative relation

5 between the two electrodes. For a sufficiently large range of variation of the flow of electrons, these conditions can be realized only if, according to the invention, the anode is heated from without either directly or indirectly and if the temperature needed for the electron emission is sustained at the cathode by virtue of the heat radiation from the anode. If the voltage drop between cathode and anode and the current heat loss caused by that voltage drop were negligibly small and if the entire condensation heat of the electrons were returned from the anode to the cathode, then the proper temperatures of anode and cathode, in this special case, could be sustained, without aid from an extraneous heat source and independently of the transmitted electron current, merely by heating the cathode by radiation from the anode. This limit condition, however, cannot practically be realized because there is always a voltage drop between cathode and anode and because, generally, the quantity of condensation heat at the anode exceeds the quantity of vaporization heat at the cathode. Nevertheless, the radiative return of condensation heat from the anode to the cathode improves the temperature conditions to such an extent that the steady-state operation becomes more independent of the transmitted electron current so that the performance of the discharge device attains a higher degree of stability.

10 If the gas discharge device serves as a rectifier, which upon polarity reversal blocks the flow of inverse current, then the cathode and anode surfaces must be differently constituted, so that, for instance, in contrast to the behaviour of a completely pure metal surface, the more highly heated anode surface has an electron emissivity of a lower order of magnitude than the cathode surface having a considerably lower temperature. Such conditions can be secured, for instance, by means of tungsten electrodes within an atmosphere of alkali metal vapor of suitable density. The less heated and slightly oxidized cathode surface is coated with an alkali metal film while the carefully cleansed anode surface has an operating temperature sufficiently high to prevent the adherence of an adsorbed film of alkali metal vapor.

15 These and other features of the invention will be explained in the following with reference to the drawing, in which

20 Figures 1 and 2 show sectional views of two respective embodiments of discharge devices according to the invention;

25 Figs. 3a and 3b, respectively, are a top view and

a sectional side elevation of an anode structure for discharge devices according to the invention;

Fig. 4 is a sectional side view of another modification of a heated anode structure suitable for devices according to the invention;

Fig. 5 is a section through a thyratron-type gas discharge device with a separately heated anode and an auxiliary electrode serving as a control grid;

Fig. 6 is a section through a gas discharge device according to the invention with two heated anodes; and

Fig. 7 is a schematic circuit diagram of a three-phase transformer-rectifier apparatus equipped with discharge devices according to Fig. 1.

Referring to the embodiment of Fig. 1, the illustrated discharge tube has an envelope 21 consisting, preferably, of an alkali vapor resistant boro-silicate glass such as known under the trade name Pyrex. The envelope is evacuated and contains a quantity of cesium. A cup-shaped cathode structure 22 is mounted on a sealed-in carrier rod 23. The anode consists of a helical tungsten filament 24 with its appertaining two inleads 25. The leads 25 are sealed through the envelope wall. The anode is rated for an operating temperature of about 2000° abs. when the anode leads 25 are connected to a source of filament heating current. At a vessel temperature of 400° to 450° C., i. e. at the cesium vapor pressure corresponding to this temperature, the surface of the highly heated anode 24 is virtually free of cesium so that its specific emissivity is at about 10^{-3} amp./cm.².

In this embodiment, the cathode 22, consisting for instance of oxidized tungsten sheet metal, is shaped substantially as a hollow cylinder and has an opening in which the anode helix 24 is located. Anode and cathode are surrounded by a radiation shield 27 secured to a sealed-in carrier 28. This tube design has the effect that the cathode is heated by radiation from the anode to the required operating temperature of, for instance, 1300° abs. At that temperature, the cathode surface is coated with a layer of cesium which, due to dynamic equilibrium between evaporation and condensation, is maintained at or near an optimum degree of coverage, thus securing a persistent high emissivity. Under such conditions a specific cathode emission of about 10 amp./cm.² is obtainable so that the ratio of cathode emission to anode emission would be in the order of 10^4 .

A cathode of the hollow design exemplified by Fig. 1 has the advantage of a very good adsorption of heat radiation from the anode. Such a cathode design also minimizes or prevents the possibility that the electrons issuing from the cathode surface may directly reach the anode without contributing to the ionization of the vapor space; the design promotes a repeated back and forth travel of the electrons within the cathode chamber and a correspondingly strong ionization of the vapor space.

While the heating of the anode 24 secures an operating temperature high enough to prevent the anode surface from being coated with an alkali metal layer appreciably increasing the emissivity of the anode metal, zones of reduced temperature may occur along the anode leads 25. This may lead to the deposition of cesium at the cooler places with an ensuing increase in emissivity which decreases the peak inverse voltage and may cause arcbreak. To prevent this, the anode leads 25 within the vessel are prefer-

ably protected from the formation of emissive coatings by a suitable surface treatment or design. For instance, as shown in Fig. 1, the anode leads 25 may be covered by coatings 26 of refractory insulating material such as zirconium oxide or aluminum oxide.

It will be recognized that in the above-described embodiment the electron condensation heat given off at the anode is radiated back to the cathode where it is needed for the further electron release and vaporization, the required operating temperature of the cathode being dependent upon this return radiation without which the cathode would cool below the needed temperature level.

A particular advantage of a discharge device according to the invention is the fact that the energy released by the electrons collected by the anode causes heating of just that electrode which is intentionally to be kept at a high temperature, contrary to conventional electronic tubes whose anode heat losses must be carried off by cooling means. This advantage can further be utilized under certain conditions, especially when the tube is to operate under a constant plate load, in having the anode maintain its required operating temperature by self heating so that an external source of heating energy is needed only for starting the operation of the discharge vessel. An example of such a self-heating anode tube is shown in Fig. 2.

According to Fig. 2, the tube envelope 31 encloses a hollow cylindrical and generally cup-shaped cathode 32 mounted on a sealed-in conductor rod 33. A plate-shaped anode 34 is located within the cup opening of the cathode and mounted on an inlead rod 35. For the reasons previously given, rod 35 is covered with an insulating coating 36. A high-frequency heating coil 30, shown in cross section, is arranged at the outside of the envelope 31 for the inductive eddy-current heating of the anode plate 34. Cathode 32 and anode 34 are surrounded by a radiation shield 37 mounted on sealed-in carriers 38. To prevent the cathode and shield from being heated by the induction coil 30, the cathode cylinder 32 and the radiation shield 37 are longitudinally subdivided or have longitudinal slots such as the one denoted by 39. The heating coil 30 is energized during starting periods to raise the electrode temperatures up to the normal operating values. Thereafter the coil 30 can be partly or wholly deenergized, letting the anode retain its temperature by self-heating due to the load current. The heated anode, in turn, then causes the cathode to maintain its required lower temperature as explained with reference to the first-described embodiment.

Figs. 3a and 3b show an example of an indirectly heated anode suitable for discharge tubes according to the invention. In these figures, the anode structure proper is denoted by 44. This hollow structure is supported by its leads 45 and has in its interior an insulated heating spiral 49, one end of which is conductively connected with one of the leads 45. A separate lead 49a is connected to the other end of the heater spiral. All three leads have non-conductive protective coatings 46 and are sealed through the wall of the vessel 41.

The hollow anode structure 54 of the modification shown in Fig. 4 contains in its interior a helical heating filament 59 which is heatable through leads 59a to an incandescent temperature. The anode structure 54 is insulated from

the filament leads and has a separate lead 55. A voltage source can thus be connected between the anode lead 55 and one of the leads 59a in order to heat the anode 54 by electronic action up to the desired operating temperature. The three leads of the anode assembly are non-conductively coated within the vessel 51 to prevent emission from these leads.

In devices according to the invention, the anode may consist of metals other than tungsten. It is, as a rule, of advantage to select an anode material whose emission characteristic for a given operating temperature is as low as possible. If a discharge device according to the invention is supposed to have especially high safety from arc-back, the operating pressure of the alkali vapor is kept relatively low because at lower vapor temperatures the ratio between the emissivity of the cathode and the emissivity of the anode is larger than in the range of higher alkali vapor pressures. Conversely, if especially high current densities are aimed at, the vessel temperatures may be given a higher value because then the absolute value of cathode emission is correspondingly increased.

In the thyratron-type discharge device shown in Fig. 5, a hollow cathode structure 61 is heated exclusively by the passage of the discharge current and by radiation from the anode. The anode structure 62 is indirectly heated by a helical filament 63. A centrally perforated auxiliary electrode 64 surrounds the anode structure to serve as a control grid. The cathode 61 is surrounded by a radiation screen 66. The current conducting inleads 69 for the anode 62 and the control grid 64 are prevented from becoming emissive by protecting insulating tubes 67, for instance of aluminum oxide, as described previously in conjunction with the embodiments of Figs. 1 to 4. The entire electrode arrangement is enclosed in a sealed glass envelope 68 containing an atmosphere of potassium, rubidium or cesium vapor. During the normal operation of the tube, the temperature of the anode 62 is higher than that of the substantially radiation heated cathode 61, and the control grid 64 assumes a temperature between the respective temperatures of anode 62 and cathode 61, this grid temperature being still high enough to prevent the formation of an electron emission coat of alkali metal on the grid electrode.

The embodiment shown in Fig. 6 is designed as a by-phase rectifier valve and is equipped with two anodes 70 and 71 within a hollow cathode structure 72. The electrodes are disposed within a sealed glass envelope 73. The envelope wall is traversed by the inleads 74 and 75, for the anode 70, and the corresponding leads 76 and 77 of the anode 71. The cathode 72 is connected to an inlead 78. A heat radiation screen 79 is fastened to carrier rods 80 and 81 which are sealed through the envelope. In the interior of the envelope 73, the anode leads 74, 75, 76 and 77 are coated with a layer 82 of zirconium oxide or aluminum oxide which prevents these leads from becoming emissive due to precipitation of alkali metal at those places where the temperature of the leads is lower than that of the anodes proper. Each of the anodes 70 and 71 consists of a helical filament, for instance of pure tungsten, which is directly heated from a suitable source of filament heating current (not illustrated). The cathode 72 is designed as a closed hollow cylinder with openings for the passage of the anode leads. The two anodes 70 and 71 are located completely within the

cathode structure. The envelope contains vapor of alkali metal, for instance, cesium. In other respects the operation of the device is similar to that of the embodiment according to Fig. 1.

When using discharge devices according to the invention for multi-phase rectification, the rectifier circuit connection may be such that the anodes are connected with one another to assume the same potential rather than the cathodes as heretofore customary. The three-phase rectifier according to Fig. 7 is designed in this manner.

The transformer-rectifier circuit of Fig. 7 is equipped with three rectifier tubes each designed according to Fig. 1. The three anodes 90, 91 and 92 of the respective tubes are directly connected with one another. This permits heating the three anodes from a common source 93 of filament current. The appertaining hollow cathodes are denoted by 94, 95 and 96, respectively. The other details of each tube are as shown in Fig. 1 and, for simplified illustration, are omitted in Fig. 7. The three tubes are connected to the respective secondary windings 98, 99, 100 of a three-phase power transformer 97 whose primary windings 101, 102 and 103 are connected to an alternating-current line. The primary windings are delta-connected, for instance, while the secondary windings are star-connected. The rectifier load is denoted by 104.

It will be understood by those skilled in the art after a study of this disclosure that various modifications and changes as regards details and design features other than those specifically mentioned can be applied without departure from the essence of the invention and within the scope of its features set forth in the claims annexed hereto.

I claim:

1. A gaseous discharge device, comprising an envelope containing an alkali metal vapor atmosphere, a hollow cathode structure in said envelope having a cathode surface of high electronic emissivity, and a heatable anode having an operating temperature higher than that of said cathode structure and being disposed in close thermic radiation coupling with said cathode structure for heating said structure by heat radiation from said anode.

2. A gaseous discharge device, comprising an envelope containing an alkali metal vapor atmosphere, a hollow cathode structure disposed in said envelope and having a cathode surface of high electronic emissivity, an anode having a normal operating temperature higher than that of said cathode structure and being disposed in close thermic radiation coupling with said cathode structure for heating said structure by heat radiation from said anode, a heating circuit energizable from without said envelope and thermally joined with said anode for maintaining it at said higher temperature.

3. A gaseous discharge device, comprising an envelope containing an alkali metal vapor atmosphere, a hollow cathode structure in said envelope having a cathode surface of high electronic emissivity, and a plurality of heatable anodes having a higher operating temperature than said cathode structure and being disposed in close thermic radiation coupling with said cathode structure for heating said structure by heat radiation from said anodes.

4. A gaseous discharge device, comprising an envelope containing an alkali metal vapor atmosphere, a hollow cathode structure in said envelope having a cathode surface of high elec-

tronic emissivity and having an opening, an anode, heating means thermally related to said anode for supplying heat thereto in addition to the heat due to the discharge between said cathode structure and said anode, said anode having in normal operation a higher temperature than said cathode structure and being disposed in said opening and in close thermic radiation coupling with said cathode structure for heating said structure by heat radiation from said anode.

5. A gaseous discharge device, comprising an envelope containing an alkali metal vapor atmosphere, a hollow cathode structure in said envelope having a cathode surface of high electronic emissivity, an anode, heating means thermally joined with said anode and having a heating circuit separate from the discharge path between said cathode structure and said anode, said anode having due to said heating means a higher operating temperature than said cathode structure and being disposed in the interior of the hollow cathode structure and in close thermic radiation coupling therewith for heating said cathode structure by heat radiation from said anode.

6. A gaseous discharge device, comprising an envelope containing an alkali metal vapor atmosphere, a hollow cathode structure disposed in said envelope and having a cathode surface of high electronic emissivity, and a heatable anode filament adapted for connection to a heat filament circuit and having in normal operation a higher temperature than said cathode structure, said filament being disposed in close thermic radiation coupling with said cathode structure for heating said structure by heat radiation from said anode.

7. A gaseous discharge device, comprising an envelope containing an alkali metal vapor atmosphere, a hollow cathode structure disposed in said envelope and having a cathode surface of high electronic emissivity, an anode structure having indirect heating means comprising a heater filament within said anode structure, said anode structure having a higher operating temperature than said cathode structure and being disposed in close thermic radiation coupling with said cathode structure for heating said structure by heat radiation from said anode.

8. In a gaseous discharge device according to claim 4, said heating means comprising auxiliary discharge means within said envelope.

9. A gaseous discharge device, comprising an envelope containing cesium vapor, a hollow cathode structure disposed in said envelope and having a cathode surface of high electronic emissivity, and a heatable anode having a higher operating temperature than said cathode structure and being disposed in close thermic radiation coupling with said cathode structure for heating said structure by heat radiation from said anode.

10. In a discharge device according to claim 1, said envelope consisting of material resistant to said vapor at its entire surface exposed to said vapor, said anode comprising a structure having a part of a temperature normally lower than said anode operating temperature, and a non-conductive protective coating disposed on said part within said envelope and consisting essentially of refractory inorganic material selected from the group of aluminum oxide and zirconium oxide.

11. A gaseous discharge device, comprising an envelope containing an alkali metal vapor atmosphere, a hollow cathode structure disposed in said envelope and having a cathode surface of high electronic emissivity, a heatable anode having in normal operation a higher temperature than said cathode structure and being disposed in said envelope in a close radiative relation to said cathode structure for heating said structure by heat radiation from said anode, and a control grid between said cathode and said anode having a normal operating temperature between the temperatures of said cathode and said anode.

12. A gaseous discharge device, comprising an envelope containing a cesium vapor atmosphere, a hollow cathode structure disposed in said envelope and having a cathode surface of high electronic emissivity, an anode, having means thermally coupled with said anode and adapted to be connected with a heating circuit for supplying to said anode heat in addition to that due to the discharge between said cathode structure and said anode, said anode having a normal operating temperature higher than that of said cathode structure and being disposed in a close thermic radiation coupling with said cathode structure for heating said cathode structure by heat radiation from said anode, and a control grid disposed between said cathode and said anode having a normal operating temperature between the respective temperatures of said cathode and said anode.
